UNITED STATES PATENT OFFICE.

EMIL SCHILL, OF NEW YORK, N. Y., ASSIGNOR TO CONTINENTAL GAS COMPRESSING CORPORATION, A CORPORATION OF NEW YORK.

APPARATUS FOR OBTAINING LIQUID HYDROCARBONS.

1,142,275.

Specification of Letters Patent.

Patented June 8, 1915.

Application filed June 1, 1914. Serial No. 842,035.

To all whom it may concern:

Be it known that I, EMIL SCHILL, a citizen of Wurttemberg, Germany, and a resident of New York city, New York, have 5 invented certain new and useful Improvements in Apparatus for Obtaining Liquid Hydrocarbons, of which the following is a specification.

This invention relates generally to apparatus adapted to be employed in the recovery in isolated liquid form of hydrocarbons of the methane series and it is particularly adapted to the production of gasolene from casing head gases, or gases having a similar 15 constitution.

In describing the apparatus I shall refer to the constituents of the gas mixture as methane, gasolene and pentane, methane being the term employed to refer to the permanent gases and pentane to the liquefiable gases whose vaporization points are lower than those of gasolene. In addition to being of special value in connection with the manufacture of gasolene, the apparatus may 20 be advantageously employed in the isolation and recovery of pentane itself, or of its adjacent hydrocarbons (hexane, etc.).

The apparatus is shown in the accompanying drawing which represents a top 30 view of the plant.

In the drawing A represents the compressor and B the belt that drives it.

C C' are the steam cylinders which communicate with the compression cylinders 35 D, D'.

E represents the pipe communicating with the source of supply such, for example, as the head of an oil well, or of a storage tank or pipe line. The mixed gases which compose this supply enter the tank F through the pipe E. The tank F is a cleaning tank and the gases entering it at the top deposit therein rust, oils, water, etc., such as are readily separated by gravity. The gases 40 thus comparatively purified pass from the tank F through pipe G to the meter M, the function of which is to measure the quantity of gases which are subsequently compressed in the cylinders D, D'. The gases first enter 45 the low pressure cylinder D and are met therein by a heat absorbing agent, such as glycerin, in the condition of very fine minute subdivision, which enters the cylinder through an atomizing nozzle supplied 50 through the pipe line L. The heat absorb- ing agent must enter the cylinder in a very finely atomized form, such as spray or mist. Glycerin may be used as the heat absorbing medium but I may employ a number of other agents which have shown satisfactory 55 results for my purposes. Any agent will be satisfactory so long as it has the quality of absorbing water, of being a good conductor of heat, of having lubricating qualities and the property of chemical neutrality with 60 respect to the products under treatment and the machinery through which it passes. It should also be constant in chemical respects; even at high temperatures and should have a high specific heat, a high specific weight, 65 a high boiling point and the capacity of being readily separated from water so that the agent may be used over and over again. I have used with good results commercial glucose, turkey red oil, glycerin, and tri- 70 methylene glycol.

After the gases have been compressed in the low pressure cylinder D, they are conveyed by means of the connection shown in the dotted lines to the high pressure cylinder 80 D', this connection being preferably located below the apparatus shown. The cylinder D' is termed a high pressure cylinder as compared with the cylinder D, although the pressure employed in my apparatus in the cylinder D' is materially less than the pressure which has been employed in connection with processes for compression of natural 85 gases. A pressure of 250 pounds in this cylinder is sufficient to bring about commercial 90 results and even lower pressures may be used. The pressure and the temperature should produce conditions such that the hydrocarbon gases still remain in their gaseous form. The heat absorbing agent removes 95 from those gases the water contained in them in the form of an aqueous vapor and also the water-soluble impurities such as NH₃, H₂S and others, as well as heavier products such as tar. The heat generated 100 by compression is not transferred to the gases, by reason, apparently of the intermolecular lubrication which seems to take place; to some extent the heat of compression is also directly absorbed by the glycerin. 105 In the high pressure cylinder D', the gases are subjected to such a degree of pressure as is required to reduce them to the proper condition for further treatment in the remainder of the apparatus and there is also

given to them the necessary power to pass through the remaining portions of the apparatus. From the high compression cylinder D' the compressed gases are brought into the top of the separator H in which the glycerin is recovered. The pipe I connects the bottom of the separator H with the top of the glycerin tank J. The pressure in the separator H is sufficient to raise the liquid in the pipe I. From the bottom of the storage tank J the glycerin is carried through the pipes K—L to the spraying nozzles through which it is injected into each of the compression cylinders in a very finely divided condition. The pipe L during a portion of its length is shown as externally cooled by the double pipe water cooler N. The by-pass O is used when the storage tank J is cut out of the system for purposes of cleaning, refilling, replacing or repair. From the upper part of the separator H the compressed hydrocarbons pass into the coil condenser P which may be cooled by the expanded gases in the manner which will be described later. The object of the condenser P is to liquefy the major portion of the hydrocarbon gases. The condensates and unliquefied gases pass through the pipe marked with an arrow from the bottom of the condenser P into the top of the collecting tank Q. Dry uncondensed gases are forced through the pipe R into the compound steam cylinders C C', where such pressure as they may be under will be converted into work. These gases as they leave the compound cylinders C C' expand into the separator S where such oils or lubricants as they may have gathered will be removed from them. The expansion of these gases at this point following the conversion of their pressure into work develops a very material reduction in temperature. The cooled gases leave the separator S through the pipe S'. The relief valve T may be used in starting the apparatus so that the gas engine shall not work against the load. The relief valve T is closed as soon as the pressure is properly developed.

To return to that stage of the process in which the condensed gases are gathered in the collecting tank Q: The liquid leaves the bottom of that tank through pipe 1 through which it is carried into the condenser 2. The condenser 2 is constructed in the form of a surface condenser being supplied with hot water through the pipe 3 which leaves the condenser at 4. The temperature of the water is so regulated that the liquid shall be heated to the desired temperature, say 60° C. The liquid or gasoline which is not vaporized in the condenser 2 is withdrawn through the pipe 5. The gases which are vaporized by this treatment in the condenser 2 leave the condenser through the pipe 6 and pass into the bottom of the coil condenser

7. The liquid condensed in the coil condenser 7 leaves through the pipe 8 at the bottom of the coil condenser and from the pipe 8 the liquid is directly collected in steel cylinders or tanks in a well known manner and under conditions which exclude the admittance of atmospheric air or pressure. Uncondensed gases may be drawn off through pipe 28.

The cooling temperature required in the condenser 7, which for convenience may be designated as the pentane condenser, as well as that required for the coil condenser P, which may be called the gasoline condenser is supplied by the system itself in the following manner: The uncondensed dry gases still under the pressure imparted to the system leave the collecting tank Q through the pipe 9 which communicates with the pipe R and thus through the compound cylinders C C' and the oil separator S. As above described the gases leave the separator S passing into the pipe 10, being now extremely cold and a part of this gas may be conveyed through the pipe 11 to the gas engine which drives the belt B. The cold gases otherwise flow onward through the pipe 10 to the cross-T 12. The gas is divided and a part of it passes into the top of the pentane condenser 7. The balance of the cooled gas is conveyed by means of the pipe 13 into the bottom of the coil in the gasoline condenser P leaving the same at the top through pipe 14, into the cross-T 15 from which they emerge from the system through the pipe 16. In the cross-T 15 these cold gases coming from the gasoline condenser P are joined by the cold gases which leave the top of the pentane condenser 7 through the pipe 17. The valves 18 and 19 are provided so as to permit the withdrawal of the cold gases from the system without causing them to pass through the gasoline condenser or to permit the regulation of the temperature in the gasoline condenser. The cold gases that leave the system at 16 may be again metered and employed for industrial purposes especially where they contain very volatile noncondensable constituents such as methane.

For the purpose of producing the pentanes in a condition of greater refinement there may be more than one pentane condenser included within the system with suitable temperature control for each. For the purpose of this invention, it is not material that all of the liquefiable constituents of the gas be liquefied in the condenser P so long as the pentane is liquefied while in the form of a separated gas, by which I mean a gas which is no longer in admixture with the original gases in the original proportions. For example, the pentane becomes a separated gas as soon as a part, or all, of the gasoline is withdrawn from the com-

pressed gases, irrespective whether the pentane is first liquefied together with the gasoline and is subsequently volatilized and reliquefied, or whether the gasoline alone is 5 first extracted from the compressed gases and the pentane separately liquefied at a separate subsequent stage of the process:

The process employed in the apparatus as above described has been patented to me 10 broadly in United States Letters Patent No. 1,100,260, issued June 16, 1914, and in this application I seek to protect broadly an apparatus in which the said process may be carried out.

15 In such cases where the production of pentanes is of particular importance, the starting material, instead of being casing head gases may be natural petroleum containing pentanes. In such cases care should be taken not 20 to permit the volatilization of the pentanes during their collection and further treatment. By heating such petroleum to say 70° C., a certain variety of hydrocarbons, including pentanes are driven off and pass 25 through the above described apparatus until they are liquefied. With liquid mixtures of this character the volatilization of the low boiling ingredients is retarded and the temperature may be advantageously increased 30 to secure a more nearly quantitative yield. The ultimate liquid obtained in this way consists substantially of pentanes, but is likely to contain a proportion of its nearest homologues. It is essential from whatever 35 source the pentanes are produced that they shall be filled into steel cylinders or the like directly from the apparatus described and that the cylinders shall be immediately sealed and protected against the admission 40 of air, after which the contents may be directly used for further industrial processes, or may be further isolated for fractional distillation, or otherwise, as above described, provided always that such further isolation 45 treatments take place in a closed system, excluding atmospheric air.

The apparatus, as above described, is in the form of a closed system which involves the compression of gas in the presence of a 50 finely divided heat absorbing medium and a withdrawal of that medium from the compressed gases. Commercial gasoline is continuously recovered at one end of the system; pentane or a similar fraction continuously at a second point and methane or permanent gases continuously at a third point.

What I claim is:

1. The combination of a compressor for compressing natural gas mixtures containing gasoline, pentane and methane, an injecting nozzle communicating with the interior of said compressor adapted for the injection of a finely divided liquid, a collector to receive liquid constituents of the compressed gases as they leave the compressor,

a condenser within which the gasoline is liquefied, a second condenser within which the pentane is liquefied while in the form of a separated gas, pipes passing through each of said condensers thereby dividing each of them into two separate passages, pipe connections for introducing the pentane as a separated gas into the pentane condenser and means for causing expansion of the separated methane component of the compressed gases and for drawing the cold expanded methane through one of the two separated passages in each of the two condensers above named while the gas to be subjected to the action of the cold methane traverses the other passages of said two condensers. 70

2. The combination of a compressor for compressing natural gas mixtures containing gasoline, pentane and methane, an injecting nozzle communicating with the interior of said compressor adapted for the injection of a finely divided liquid, a collector to receive liquid constituents of the compressed gases as they leave the compressor, a condenser within which the gasoline is liquefied, a second condenser within which the pentane is liquefied while in the form of a separated gas, pipes passing through each of said condensers thereby dividing each of them into two separate passages, pipe connections for introducing the pentane as a separated gas into the pentane condenser, means for causing expansion of the separated methane component of the compressed gases and for drawing the cold expanded methane through one of the two separated passages in each of the two condensers above named while the gas to be subjected to the action of the cold methane traverses the other passages of said two condensers, and means 90 for separately drawing off gasoline, pentane and methane without interrupting the operation of any of the foregoing apparatus, the entire apparatus above named, except for the drawing off channels, being arranged to 95 form a closed system.

3. The combination of a compressor for compressing natural gas mixtures containing gasoline, pentane and methane, an injecting nozzle communicating with the interior of said compressor adapted for the injection of a finely divided liquid, a collector to receive liquid constituents of the compressed gases as they leave the compressor, a condenser within which the gasoline is liquefied, a second condenser within which the pentane is liquefied while in the form of a separated gas, pipes passing through each of said condensers thereby dividing each of them into two separate passages, pipe connections for introducing the pentane as a separated gas into the pentane condenser and a methane line including therein means for permitting the methane to expand and for conducting the expanded methane 115 120 125

through one of the separated passages of each of the above mentioned two condensers while the gas to be subjected to the action of the cold expanded methane traverses the other passage of said condensers.

4. The combination of a compressor for compressing natural gas mixtures containing gasolene, pentane and methane, an injecting nozzle communicating with the interior 10 of said compressor adapted for the injection of a finely divided liquid, a collector to receive liquid constituents of the compressed gases as they leave the compressor, a condenser within which the gasolene is liquefied, a second condenser within which the pentane is liquefied while in the form of a separated gas, each of said two collectors consisting of two separated passages so arranged that one should be subject to tem-

perature conditions in the other, pipe connections for introducing the pentane as a separated gas into the pentane condenser and means for causing expansion of the separated methane component of the compressed gases and for drawing the cold expanded methane through one of the two separated passages in each of the two condensers above named while the gas to be subjected to the action of the cold methane traverses the other passages of said two condensers.

In testimony whereof, I have hereunto set my hand in the presence of two subscribing witnesses.

EMIL SCHILL.
